COMBINED ASH TRAY AND CIGARETTE
SNUFFERWalter E. Wood, 128 Platte St., P.O. Box 1269,
Sterling, Colo. 80751

Filed Dec. 27, 1966, Ser. No. 5,182

Term of patent 14 years

(Cl. D85—2)

Fig. 1

Fig. 2

Fig. 3

Fig. 4

FIG. 1 is a perspective view of a combined ash tray and cigarette snuffer showing my new design with the cover in closed position;

FIG. 2 is a reduced scale top plan view thereof;

FIG. 3 is a perspective view from the side opposite that shown in FIG. 1, with the cover in open position; and

FIG. 4 is a reduced scale elevational view taken from the bottom of FIG. 2.

I claim:

The ornamental design for a combined ash tray and cigarette snuffer, as shown.
